(57) **CLAIM**

The ornamental design for an electrosurgical pencil with notched and scalloped handle.

DESCRIPTION

FIG. 1 is a perspective view of the electrosurgical pencil with notched and scalloped handle;

FIG. 2 is a top view thereof;

FIG. 3 is a bottom view thereof;

FIG. 4 is a left side view thereof;

FIG. 5 is a front view thereof;

FIG. 6 is a right side view thereof; and,

FIG. 7 is a rear view thereof.

The broken lines shown in FIGS. 1–7 are for illustrative purposes only and form no part of the claimed design.
